US00D506633S

(12) **United States Design Patent** (10) Patent No.: **US D506,633 S**
Dick-Read (45) Date of Patent: **** Jun. 28, 2005**

(54) **DEVICE FOR MAKING A BEVERAGE**

(75) Inventor: **Giles Dick-Read, Oxfordshire (GB)**

(73) Assignee: **Tea Solutions Limited (GB)**

(**) Term: **14 Years**

(21) Appl. No.: **29/198,396**

(22) Filed: **Jan. 29, 2004**

(30) **Foreign Application Priority Data**

Aug. 1, 2003 (EM) 000058938

(51) LOC (8) Cl. **07-99**
